UNITED STATES PATENT OFFICE.

THOMAS MACREADY DOWN, OF HAMMERSMITH, LONDON, ENGLAND.

DESIGN FOR A SET OF PLAYING-CARDS.

45,449.

Specification for Design.

Patented Mar. 24, 1914.

Application filed December 31, 1912. Serial No. 739,576. Term of patent 14 years.

To all whom it may concern:

Be it known that I, THOMAS MACREADY DOWN, subject of the King of Great Britain, residing at 3 Hauteville Court Gardens, Hammersmith, London, England, have invented a new, original, and ornamental Design for a Set of Playing-Cards, of which the following is a specification, reference being had to the accompanying drawing, forming part thereof.

The figures are views of a set of playing cards, showing my new design for cards having the value 14, which cards are intended to be used in extension of the ordinary four suits of 13 cards of a pack of playing cards.

I claim:

The design for a set of playing cards, as shown.

In testimony whereof I have signed my name to this specification in the presence of two subscribing witnesses.

THOMAS MACREADY DOWN.
